UNITED STATES PATENT OFFICE.

AUGUST T. PETERSON, OF BROOKLYN, NEW YORK.

DEVICE FOR OVERCOMING DEAD-CENTERS.

1,084,821.

Specification of Letters Patent.

Patented Jan. 20, 1914.

Application filed January 8, 1913. Serial No. 740,066.

To all whom it may concern:

Be it known that I, AUGUST T. PETERSON, a citizen of the United States, residing at Brooklyn, in the county of Kings and State 5 of New York, have invented certain new and useful Improvements in Devices for Overcoming Dead-Centers, of which the following is a specification.

This invention relates to improvements in 10 devices for overcoming dead centers in crank shafts, crank wheels, etc., and is especially designed for use upon driven crank shafts.

The primary object of the invention resides in the provision of a device of this nature, which may be easily and quickly adjusted so as to vary the tension of the spring which exerts its pressure upon the fly-wheel.

Another and more specific object of the invention is to provide a device of this nature, including a convolute spring, a plurality of spiral springs bearing against said convolute spring, and a movable casing to contain said springs.

The invention also aims to generally improve devices of this nature to render them more simple, efficient, useful, and commercially desirable.

With these and other objects in view, as will become more apparent as the description proceeds, the invention consists in certain novel features of construction, combination, and arrangement of parts, as will be hereinafter fully described and claimed.

For a complete understanding of the invention, reference is to be had to the following description and accompanying drawings, in which,

Figure 1 is a side elevation of my invention, showing the same connected to a fly-wheel, Fig. 2 is an edge elevation, Figs. 3 and 4 are views taken upon the planes of lines 3—3 and 4—4, respectively, of Fig. 1 and Fig. 4 has the spring omitted.

Referring in detail to the drawings by numerals, 1 designates a crank shaft, 2 the bearing standards supporting the same, 3 a pulley rigid with the crank shaft, 4 a pitman, and 5 a fly-wheel. These elements are of the usual type and I make no claim to 50 them.

My invention includes an arcuate casing 6 formed of a ring of metal partly broken away, as clearly shown in Fig. 1, and cast integral with a base 7. The base is preferably of the same width as the casing and has formed in its lower side a longitudinal

channel to receive a track 8. A spur gear 9 is mounted upon one side of the base 7 to mesh with a rack 10, which extends parallel to the track 8, upon one side of said base. A 60 crank arm 11 is employed to actuate the gear 9, whereby the casing may be moved longitudinally of the track 8. Oppositely extending pivoted pawls 12 and 13 are mounted upon the base 7 for engagement 65 with the rack 10, holding the base 7 immovable. Springs 14 retain the pawls normally in engagement with said rack but a pressure upon the inner ends of the pawls will suffice to raise them from engagement with the 70 rack, in order that the base may be moved in the direction desired.

A standard 15, preferably formed integral with the base 7, extends upwardly from adjacent one side thereof and terminates centrally of the casing 6. A cap plate 16 is mounted upon the top of the standard 15 and secures thereto a pin or stub shaft 17 upon which is mounted a split block 18. The two sections of the block are clamped 80 together by suitable fasteners 19, said fasteners also securing one end of a convolute spring 20. The spring extends partly around the casing 6, as clearly shown in Fig. 1, and is connected at its other end to 85 a split block 21, by means of suitable fasteners 22. The block 21 is mounted upon an eccentric pin 23, formed upon one spoke of the fly-wheel 5.

A plurality of radially extending guides 90 24 are formed upon the casing ring 6 and terminate in spaced relationship with the block 18. These guides are formed in pairs, as clearly shown in Figs. 3 and 4, and have their inner surfaces concave so as to retain 95 therebetween expansive spiral springs 25. The guides of each pair are spaced from each other to receive the convolute spring 20. This spring extends upwardly from the block 18, then around the casing, essentially 100 parallel to the inner wall thereof, and is held against lateral movement by the guides 24. The expansive spiral springs 25 bear against the convolute spring 20, as will be clearly apparent from the drawing. If desired, a flat metal spring 26 may be secured to the standard 15 and bear against the convolute spring 20, so as to increase the effect 105 of said spring upon the fly-wheel.

In operation, the pitman 4 drives the crank 110 shaft 1 and rotates the fly-wheel 5, which expands and contracts the convolute spring

20. This spring is attached to the fly-wheel so as to force the same over the points of dead center. It will be seen upon reference to Fig. 1, that the free end of the convolute spring will have a tendency to upward and forward movement, the force of which is increased by the action of the spiral springs 25 and flat metal spring 26 that bear against said convolute spring. The tension of the 10 convolute spring and also the tension of the spiral springs 25 may be suitably adjusted by moving the casing 6 toward or away from the crank shaft 1, it being understood that the track 8 extends at right angles to 15 said shaft. It is to be understood that I may employ any number of these devices and may connect them in different ways to the crank shaft.

While I have shown and described the 20 preferred embodiment of my invention, it is to be understood that I do not wish to be limited to this exact construction, combination, and arrangement of parts, but may make such changes as will fall within the 25 spirit and scope of the invention.

Having thus described my invention, what I claim is:—

1. A device for overcoming dead centers, comprising a crank shaft, a fly wheel mounted on said crank shaft, a convolute spring 30 adapted to be secured at one end to said fly-wheel, a support for the other end of said spring, and a plurality of spiral springs acting against said convolute spring.

35. 2. A device for overcoming dead centers, comprising a crank shaft, a fly wheel mounted on said crank shaft, a convolute spring adapted to be secured at one end to said fly-wheel, a movable support for the other end 40 of said convolute spring, and a plurality of expansive spiral springs acting against the outer surface of said convolute spring.

45. 3. A device for overcoming dead centers, comprising a crank shaft, a fly wheel mounted on said crank shaft, a convolute spring adapted to be attached at one end to said fly-wheel, means for supporting the other end of said convolute spring, a casing partly surrounding said spring and provided with a 50 plurality of radially extending guides

through which the spring projects, and a plurality of spiral expansive springs positioned within said guides and bearing against the convolute spring.

4. A device for overcoming dead centers, 55 comprising a crank shaft, a fly wheel mounted on said crank shaft, an arcuate casing, a plurality of spaced guides extending radially inwardly from said casing, a standard rigid with said casing and terminating centrally thereof, a convolute spring supported upon said standard and extending between said guides, the other end of the spring being adapted to be secured to said fly-wheel, a plurality of expansive spiral springs bearing 60 against the exterior surface of said convolute spring, and means whereby said casing may be moved toward or away from the fly-wheel to adjust the tension of the springs. 65

5. The combination with a crank shaft 70 and fly-wheel, of a device for overcoming dead centers, comprising an arcuate casing, a base formed integral with said casing having a longitudinal channel extending entirely therethrough, a track extending at 75 right angles to said crank shaft, means for moving said casing longitudinally of the track, and a convolute spring secured at one end within said casing and at its other end to said fly-wheel. 80

6. The combination with a crank shaft and fly-wheel, of a track extending at right angles thereto, a casing, a base movable upon said track, a rack, a spur gear journaled upon the base to mesh with the rack, means 85 for actuating said spur gear, whereby the base will be moved, means to lock the base against movement, an arcuate casing formed integral with said base, a convolute spring secured at one end within said casing and at 90 its other end within said fly-wheel, and additional springs bearing upon said convolute spring. 95

In testimony whereof I affix my signature in presence of two witnesses.

AUGUST T. PETERSON.
